CARDIAC RESUSCITATOR

Stanley F. Meyer, 6598 Mount Ripley Drive,
Buena Park, Calif. 90620

Filed May 5, 1970, Ser. No. 22,816

Term of patent 14 years

Int. Cl. D24—02

U.S. Cl. D83—1

FIG. 1 is a perspective view of a cardiac resuscitator embodying my new design,

FIG. 2 is a side elevation thereof, showing the side not shown in FIG. 1,

FIG. 3 is an end view thereof, as viewed from the right in FIG. 2, and

FIG. 4 is a bottom plan view.

I claim:

The ornamental design for a cardiac resuscitator, substantially as shown.
